UNITED STATES PATENT OFFICE

2,446,139

VALVE

Barney J. Lyons, Nashville, Tenn.

Application April 24, 1947, Serial No. 743,608

4 Claims. (Cl. 277—7)

1

The present invention relates generally to the class of valves, and more specifically to an improved water supply protector and regulator or multi-valve appliance, which, while well adapted for controlling the flow of fluids under pressure, is especially designed as a protective element for installation in water supply pipes in connection with domestic and other water pressure systems. By the installation and utilization of the appliance of my invention back pressure or drainage from a supplied system to a water main is prevented, thus eliminating possibility of contamination of the main water supply; a water lock within the appliance is prevented; and means are provided for discharging excess or waste water from a supplied system, without interference with the free flow of water from the water main to the supplied system. While constantly supplying and regulating the flow of water from the water main to the supplied system, the latter is also automatically protected by the appliance from any excessive pressure in the water main.

The valved appliance of my invention is composed of a minimum number of standardized parts that with facility and low cost of production may be manufactured, and the component parts may be assembled with facility, to provide a durable, reliable, and efficient water-pipe fitting which may be installed with ease and dispatch.

The invention consists in certain novel features of construction and combinations and arrangements of parts involving a valve casing and multiple interior hinged and suspended valves actuated under fluid pressure, as will hereinafter be described and more particularly pointed out in the appended claims.

In the accompanying drawings I have illustrated one complete example of a physical embodiment of my invention in which the component parts are combined and arranged in accord with a mode I have devised for the practical application of the principles of my invention. It will however be understood that changes and alterations are contemplated and may be made in these exemplifying drawings and mechanical structures, within the scope of my claims, without departing from the principles of the invention.

Figure 1 is a vertical longitudinal sectional view of an appliance in which my invention is embodied; and

Figure 2 is a transverse vertical sectional view, as at line 2—2 of Fig. 1.

In the assembly view I utilize a cast metal fitting or valve casing 1, preferably formed with flattened side walls, and an upper inclined front

2

wall fashioned with an exterior threaded flange 2 surrounding an opening and normally closed by a removable assembly cap or plug 3, which permits access to the interior of the casing for assembling the interior operating parts of the appliance.

The interior of the casing is divided by an integral vertical transversely arranged partition 4 to form at one side an intake chamber for water under pressure to be supplied through a supply pipe 5 at the front or outer side of the casing; and at the inner or rear side of upright partition, an integral horizontal partition 6 forms a waste discharge chamber having an outlet or waste pipe 7 and an outlet or delivery chamber opening to a delivery pipe 8 that is aligned with the intake pipe 5, and of the same capacity and diameter for supplying water to the water system of which the appliance forms a part.

For controlling the supply of water from the intake pipe to the delivery or outlet pipe, and for regulating the discharge of waste water as well as for relieving excessive fluid pressure within the valve casing, I provide multiple valves of the hinged and suspended flap type which are arranged to open and close ports under fluid pressure, and a lower intake port 9 of the casing from the supply pipe or inlet pipe 5 is controlled by valve 10. This one-way or check valve, which opens inwardly under fluid pressure is in the form of a circular disk that is pivotally suspended on pin 11 that is mounted upon the interior face of the wall of the intake chamber. The valve structure includes a vertically disposed arm 12 that is secured by stud bolt 13 and nut 14 to the disk 10, and the valve under fluid pressure from the water main is adapted to swing inwardly on its pin to open position for flow of water into the intake chamber; the opening movement of the valve being limited by means of a stop lug 15 on the lower end of the arm 12.

From the intake chamber water under pressure is adapted to flow through a circular outlet port or passage 16 into the outlet chamber, and thence through the outlet pipe 8 to the water system being supplied with water. For controlling the flow of water through the port or passage 16 a hinged disk valve 17 is located in the delivery chamber and adapted to open outwardly, and the valve is mounted on an arm 18 that is pivotally suspended on pin 19.

This delivery valve, it will be seen in pivotally mounted upon a comparatively large differential and back pressure valve 20 located in the intake chamber, for controlling a larger port 21 in the

upright partition 4, and the outlet valve 17 when closed is located in this large port.

The back pressure valve 20 is provided with a tubular boss that forms the port or passage 16 for the outlet or delivery valve 17 and the boss passes through a long arm 22 of the differential valve and is secured thereto by lock nut 23, and the arm is suspended to swing with the valve on a pivot pin 24 mounted in supporting ears near the top of the upright partition 4.

For discharging waste water from the intake chamber the inwardly opening differential valve 20 is equipped with a hinged and suspended discharge valve 25 that normally closes the inner port of a passage 26 in the upper portion of the upright partition 4, and as shown valve 25 that is located in the intake chamber swings to open position with the differential valve 20, under back pressure from the water system.

Valve 20 and valve 25, are rigidly attached to the long arm 22, and valve 20, which is arranged eccentrically of the delivery valve 17, is provided with a centering pin P that passes through a hole bored in the arm 22 for use in assembling the parts.

At the waste discharge side of the partition 4 the outlet port of the passage 26 is controlled by another hinged valve 27 that is suspended in the discharge chamber on pivot pin 28, and the opening movement of this check valve or one-way valve is governed or regulated by means of a set screw 29 threaded through a bore in the upper wall of the valve casing. The set screw projects into the path of movement of a stop lug 30 of the valve 27, and a spring 31 is provided to afford a resilient pressure against the lug. By means of the spring and set screw the opening of the valve 27 may be regulated for a predetermined back pressure in the casing.

From this description taken in connection with the drawings it will be evident that when the valve 10 is opened under fluid pressure from the water main, water flows into the intake chamber, closing the differential or back-pressure valve 20 and the discharge valve 25, and opening the delivery valve 17 for passage of water through the delivery chamber into the pipe 8.

To prevent back drainage from the water system through the valve casing to the water main that might contaminate the water in the main, and to relieve any excessive back pressure from the water system in case of a negative pressure on the intake valve 10, if and when the fluid pressure in the delivery chamber is sufficient to open valve 20, the intake valve 10 is closed. The swinging movement of arm 22 of the back pressure valve also opens the discharge valve 25 to flow of excess water through port 26, thereby opening the waste valve 27 for disposal of excess pressure through the drainage pipe 7.

Having thus fully described my invention, what I claim as new and desire to secure by Letters Patent is:

1. In a fluid pressure water control appliance the combination with a casing having interior separated intake, delivery, and discharge chambers and valve-ports for said chambers, of a pivotally suspended intake valve in the intake chamber, a pivotally suspended delivery valve in the delivery chamber, means for trapping water under back pressure from the delivery valve in the intake chamber and a pivotally suspended discharge valve opening from the intake chamber to the discharge chamber.

2. In a fluid pressure water control appliance, the combination with a casing having a ported vertical integral partition and a closed horizontal partition forming an intake chamber, a delivery chamber and a discharge chamber, of a pivotally suspended valve opening into the intake chamber, of an outwardly opening delivery valve in the delivery chamber, means for trapping excess back-pressure fluid in the intake chamber, and means for draining said back pressure fluid into the discharge chamber.

3. In a fluid pressure water-control appliance, the combination with a casing having a ported vertical partition and a closed horizontal partition forming an intake chamber, a delivery chamber, and a discharge chamber, of an inwardly opening intake valve, a pivotally suspended back pressure valve in the intake chamber controlling a port in the vertical partition, a delivery valve opening outwardly in the delivery chamber and controlling a port in said back-pressure valve, means for pivotally suspending the delivery valve on the back-pressure valve, and means for draining back-pressure water from the intake chamber into the discharge chamber.

4. In a fluid pressure water-control appliance, the combination with a casing having separate intake, delivery, and discharge chambers, of an inwardly opening inlet valve in the intake chamber controlling an intake port, a back-pressure valve in the intake chamber controlling a port between the intake and delivery chambers, a delivery valve mounted on said back-pressure valve controlling a port between the intake and delivery chambers, a discharge valve means for connecting the discharge valve and back-pressure valve, said back-pressure valve controlling a port to the discharge chamber, and a check valve mounted in the discharge chamber also controlling the last mentioned port.
